UNITED STATES PATENT OFFICE.

ALFRED A. BOYCE, OF BARRE, VERMONT.

FOLDING-MACHINE.

1,138,185.

Specification of Letters Patent.

Patented May 4, 1915.

Application filed January 14, 1914. Serial No. 812,076.

To all whom it may concern:

Be it known that I, ALFRED A. BOYCE, a citizen of the United States, residing at Barre, in the county of Washington and State of Vermont, have invented certain new and useful Improvements in Folding-Machines, of which the following is a specification, reference being had to the accompanying drawings.

10 This invention relates to certain improvements in folding machines and has relation more particularly to a device of this general character especially designed and adapted for use in folding slips for mail pouches and the object of the invention is to provide a device of this general character having means of a novel and improved character whereby a slip may be folded in substantially an automatic manner and whereby such slip after being folded may be properly stamped.

15 The invention consists in the details of construction and in the combination and arrangement of the several parts whereby certain important advantages are attained and the device is rendered simpler, less expensive and otherwise more convenient and advantageous for use, all as will be hereinafter more fully set forth.

20 The novel features of the invention will be carefully defined in the appended claims.

25 In order that my invention may be the better understood, I will now proceed to describe the same with reference to the accompanying drawings, wherein—

30 Figure 1 is a view in top plan of a folding machine constructed in accordance with an embodiment of my invention; Fig. 2 is a sectional view on the line 2—2 of Fig. 1, with a coacting element being indicated by dotted lines; Fig. 3 is a sectional view taken substantially on the line 3—3 of Fig. 1; Fig. 4 is an enlarged sectional view, illustrating certain details of my invention, as herein embodied, and showing the initial application of the slip to be folded; Fig. 5 is a view similar to Fig. 4, showing the condition of the slip before it is passed between the folding rollers; Fig. 6 is a view, partly in section and partly in elevation, showing the slip passing through the folding rollers; and Fig. 7 is a view in end elevation of a slip after being folded by my improved machine.

35 As disclosed in the accompanying drawings, 1 denotes a base which may be of any

suitable configuration and produced from any desired material and which is provided with suitable bearings 2—2 in which is rotatably supported the elongated shaft member 3, provided with suitable means whereby the same may be caused to rotate, such means being herein disclosed as a conventional crank 4 adapted to be suitably engaged with one extremity of such shaft 60 member 3.

45 Fixedly supported in a bearing 5 and disposed parallel with the shaft member 3 is the short shaft 6 on which is rotatably mounted a gear wheel 7 of predetermined 70 size which is adapted to mesh with the interrupted gear 8 fixed to the shaft member 3, the extent of the teeth 9 on the interrupted gear 8 being such as to cause the gear 7 to make a one-half revolution upon one complete revolution of the shaft member 3, for purposes which will hereinafter be made more apparent.

50 Carried by one face of the gear 7 and adapted to rotate therewith is a plate 10, 80 to the opposite extremities of which are rotatably connected, as at 11, the spindles 12—12 which spindles are caused to project through a frame 14 carried by the plate 10, whereby such spindles 12 are effectively 85 maintained in operative position. Each of the spindles 12 is provided adjacent its inner extremity with an annular toothed member 15 affording a gear adapted to mesh with the pinion or gear 16 fixed to the stationary shaft 6, whereby it will be readily perceived that while the spindles 12—12 are caused to travel concentrically about the shaft 6, they will also be caused to have individual rotary movement.

55 Each of the spindles 12 has its free extremity provided with the elongated longitudinally directed slot or recess 17 in which is adapted to project an end marginal portion of a slip *a* to be folded and in order 100 that such strip when engaged with a spindle may be caused to be wound therearound I have extended substantially half-way around each of such spindles the annular casing 18 carried by the frame 14, whereby 105 it is assured that upon the rotation of the spindle, such slip *a* is maintained upon the spindle. At the same time that the spindles are being caused to rotate, the one to which the slip *a* is applied is caused to be positioned substantially in advance of the co-acting rollers 19 and 20, so that an end por- 110

tion of the slip α wound upon a spindle and projecting beyond an extremity thereof may be engaged between the bight of such rollers and withdrawn from the spindle between the rollers whereby it will be perceived that such slip α is properly folded, the circumference of the spindle determining the extent of the folds. As is believed to be self-evident, the spindles 12 and their concomitant parts serve as a delivery mechanism.

It is to be observed that when a spindle is adjusted in proper position relative to the rollers 19 and 20 that the teeth 9 of the gear 8 are disengaged from the gear 7, whereby such spindle will be maintained substantially stationary and that the second spindle will be positioned to afford convenient and ready access thereto to apply a second slip α .

While the rollers 19 and 20 may be caused to rotate in any desired manner, I prefer to have their peripheries frictionally engaged whereby it is only necessary to provide a driving means for one of such rollers and, as herein shown, the roller 19 has its shaft 21 provided at one extremity with a gear 22 in mesh with a suitable gear 23 fixed to the shaft member 3.

In order that the slip α to be folded may readily enter between the bight of the rollers 19 and 20, I have a portion of the periphery of one of such rollers flattened tangentially, as indicated at 24, so that an effective opening is afforded for the entrance of the slip α when such slip approaches the rollers.

The slip α , after being folded by the rollers 19 and 20, is delivered to a suitable stall 25 into which the slips will pass, while each succeeding slip α is adapted to pass beneath the previous one and in order that the folded slip α may be conveyed within the stall, I employ the rollers 27 interposed between the rollers 19 and 20 and the stall 25 and which are adapted to engage the under surface of the folded slip α and by this rotary movement convey the same within the stall, and in order to assure proper engagement of these rollers 27 with the slip, I provide such rollers with the teeth 28 disposed around about one-third of their circumferences which assures the proper frictional engagement. While such rollers 27 may be caused to rotate in any desired manner, I find it of advantage to fix the same to a suitable shaft 29 having one extremity provided with a gear 30 adapted to mesh with a gear 31 also fixed to the shaft member 3. The wheels 27 frictionally engage the folded slip and force the same within the stack as such slips are extremely small and are of extremely light weight. It will also be apparent that the rollers 19 and 20, to a certain degree, force the slips within the stack.

From the foregoing description, it will be readily perceived that I have produced a device which will readily and conveniently fold slips or the like and in order that the locality from which the mail pouches are to be shipped and the date of such shipment may be marked on each of the slips one of the rollers, as 19, serves as an impression cylinder and has provided on its periphery the requisite printing face, as indicated at 31. As the details of the printing face form no particular part of my present invention, a detail thereof is believed unnecessary. The upper roller 20 serves as a carrying cylinder and positioned below the roller 19 and in contact therewith, I provide the fountain cylinder 33 fixed on a suitable shaft 34 and in frictional engagement with the roller 19, although I do not wish to be understood as limiting myself to any particular means for operating this roller 33. As herein disclosed, this roller 33 is provided with an absorbent blanket 36, to which is adapted to be applied an ink of the character generally employed with hand stamps or the like.

From the foregoing description, it is thought to be obvious that a folding machine constructed in accordance with my invention is of an extremely simple and comparatively inexpensive nature and is particularly well adapted for use by reason of the convenience and facility with which it may be employed for folding slips especially of a character adapted to be employed in connection with mail pouches and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

Having thus fully described my invention what I desire to claim and secure by Letters Patent, is:

1. A device of the character described including a folding means and a delivery mechanism coacting with said folding means and comprising a rotatable member movable relative to the folding means, a substantially rigid member rotatably supported by the first mentioned member and provided in its surface with a groove extending to the outer extremity thereof, said outer extremity of the second mentioned member being brought into close proximity to the folding means by the movement of the first mentioned member, and a casing fixedly secured to the first mentioned member disposed partially around said second member and positioned in close proximity thereto.

2. A device of the character described including a folding means and a delivery

mechanism co-acting with said folding means and comprising a rotatable member movable relatively to the folding means, a substantially rigid member rotatably supported by the first mentioned member and provided in its surface with a groove extending to the outer extremity thereof, such outer extremity of the second mentioned member being brought into close proximity to the folding means by the movement of the first mentioned member, and a casing fixedly secured to the first mentioned member and disposed in close proximity to the second mentioned member.

15 3. A device of the character described including a folding means and a delivery mechanism coacting with said folding means and comprising a rotatable member mov-

able relative to the folding means, a substantially rigid member rotatably supported by the first mentioned member and provided with a radially disposed elongated open ended slot, the outer extremity of the second mentioned member being brought into close proximity to the folding means by the movement of the first mentioned member, and a casing fixedly secured to the first mentioned member and disposed in close proximity to the second mentioned member.

In testimony whereof I hereunto affix my 30 signature in the presence of two witnesses.

ALFRED A. BOYCE.
